CLAIM

The ornamental design for a docking station with retractable cable, as shown and described.

DESCRIPTION

FIG. 1 is a front, top perspective view of a first embodiment of a docking station with retractable cable, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is another perspective view of the docking station with retractable cable, shown in an alternative position;

FIG. 11 is a front, top perspective view of a second embodiment of the docking station with retractable cable;

FIG. 12 is a rear, bottom perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof;

FIG. 18 is a bottom plan view thereof;

FIG. 19 is an enlarged view of detail "19" identified in FIG. 11; and,

FIG. 20 is another perspective view of the docking station with retractable cable, shown in an alternative position.

The dashed lines in the figures illustrate the portions of docking station with retractable cable that form no part of the claimed design. The dash dot dash lines in FIGS. 1, 9, 11 and 19 are for the purpose of illustrating the enlarged view indicators and form no part of the claimed design.
